CLAIM

The ornamental design for a ceiling fan, as shown and described.

DESCRIPTION

FIG. 1 is a bottom perspective view of a ceiling fan showing our new design;

FIG. 2 is a top perspective view of the ceiling fan of FIG. 1; FIG. 3 is a front side view of the ceiling fan of FIG. 1, with rear, right, and left side views being mirror images thereof; FIG. 4 is a bottom view of the ceiling fan of FIG. 1; and, FIG. 5 is a top view of the ceiling fan of FIG. 1. Portions of the ceiling fan shown in broken lines form no part of the claimed design.
